UNITED STATES PATENT OFFICE.

CHARLES DE MARCO, OF ROCHESTER, NEW YORK.

PRINTING-FRAME.

1,236,683.

Specification of Letters Patent. Patented Aug. 14, 1917.

Application filed September 19, 1916. Serial No. 121,061.

To all whom it may concern:

Be it known that I, CHARLES DE MARCO, a citizen of the United States, residing at Rochester, in the county of Monroe and 5 State of New York, have invented certain new and useful Improvements in Printing-Frames, of which the following is a specification.

The object of this invention is to provide 10 a new and improved form of printing frame.

Another object of the invention is to provide means where the film or plate and the sensitized paper can be brought together 15 with the vignette for the purpose of printing.

Another object of the invention is to secure the ready and easy adjustment of the film or plate and the vignette with relation 20 to each other.

These and other objects of the invention will be fully illustrated in the drawings, described in the specification and pointed out in the claims at the end thereof.

25 In the accompanying drawings,

Figure 1 is a plan view of the back of the printing frame.

Fig. 2 is a side elevation of the left hand side of the printing frame shown in Fig. 1.

30 Fig. 3 is a longitudinal section through the printing frame on the line 3^x—3^x of Fig. 1.

Fig. 4 is a transverse section on the line 4^x—4^x of Fig. 1.

Fig. 5 is a section on the line 5^x—5^x of 35 Fig. 2.

Fig. 6 is a detail view of the vignette on a reduced scale.

In the drawings like reference numerals indicate like parts.

40 In the drawings reference numeral 1 indicates the printing frame having compartments 2 and 3 located at the opposite ends thereof. Located in these compartments are the rollers 4 and 5 which are used for carrying the photographic film from which the printing is to be done and the rollers 6 and 7 which carry the vignette strip. Each of these compartments is closed by metal doors 8 and 9 hinged to the frame by which the 45

50 contents thereof are kept concealed and protected. These doors are held in place by the buttons 10, 10 and 11, 11. In the front of the printing frame is an opening 12 which is covered over at the back by a glass plate 55 13 and which is closed at the front by a hinged door 14 provided with a lock 14^a.

The vignette strip 15 travels across the opening immediately in contact with the glass plate. The photographic film 16 travels across the glass plate immediately behind 60 the vignette strip.

Keyed to the rollers 4 and 6 on one side of the printing frame are the knurled wheels 17 and 18 and keyed to the rollers 5 and 7 on the other side of the frame are the knurled 65 wheels 19 and 20. Each of these rollers is made similar to the ones shown in Fig. 5. Each roller has a slot 21 therein running substantially the length thereof and has a reduced end 22 which extends through the 70 casing to which the knurled wheel is attached. Surrounding this reduced end is a helical spring 23 which bears against the inside of the bearing plate 24 and serves to hold the rollers correctly in line and gives 75 it a frictional contact with the casing by which accidental rotation of it is prevented.

The back of the printing frame is closed by combination door which comprises a central jamb 25 to which are hinged on the opposite sides thereof the doors 26 and 27. On this jamb between the hinges is carried a block 28 on which is mounted a plate 29, the ends of which project slightly beyond the edges of the block. This block is grooved as 80 indicated at 30 in which groove is nested the spring 31. Mounted to turn on this spring is the button 32 which engages in recesses 33 and 34 on opposite sides of the frame. The upper edge of each of these recesses is finished by a metal plate, which plates are notched with square shoulders as indicated at 50, the shoulders on the edges of which notches engage on either side of the ends of the button and serve to positively hold the 90 button in place. See dotted lines in Fig. 2. The spring 31 and button 32 are provided centrally and engage with a screw or pivot pin 35 on which the button can swing freely. This button is calibrated for linear measurement as indicated in Fig. 1 so that the positioning of the card and the vignette with 95 regard to each other can be more readily determined by reference thereto.

Pivoted on each of the doors 10^a 26 and 27 are the springs 36 and 37, these springs being pivoted on screws 38 and 39. Each of these springs is bowed in the middle and has a rounded end which engages the outwardly projecting ends of the plate 29. 110 The ends of the spring can be sprung up or down past the end of the plate 29 and after

being disengaged therefrom can be swung sidewise to permit the turning of its door. After the door is closed the spring is swung in line with the plate 29, after which the 5 spring is flexed and the end thereof is placed in engagement with the underside of the plate.

Mounted in the sides of the frame are the rollers 40 and 41 which are intended to carry 10 the roller film of small width. These rollers are covered by the shields 42 and 43 on the sides of the frame. These rollers are similar in construction to the roller 6 shown in Fig. 5 and the ends of them project 15 upwardly through the case out of line with the rollers 4 and 6 and at right angles thereto and are provided on the ends thereof with knurled heads 44 and 45. By turning the one or the other of these knurled 20 heads a small film may be drawn forward or back.

It will be understood that films of small size will be used on the rollers 40 and 41 and films of larger or standard sizes will be 25 used on the rollers 4 and 5, although a small film may also be placed on the rollers 4 and 5 and shifted along the rollers to print the picture on the side or middle of the card as may be desired.

30 In operation the metal doors 8 and 9 and the proper vignette and film strips are placed on the rollers and stretched between them. The doors are then closed and the post card or other suitable print is put in 35 position as indicated at 46 in Fig. 3. The back door 25, 26 and 27 is then put in place. The front door 14 may then be opened and the film and vignette may be adjusted to proper position by turning the appropriate 40 rollers at the one or the other end of the frame. If the film or vignette do not move easily, the button 32 may be released to relieve the pressure. After the film and vignette have been properly placed the door 14 45 may then be opened in suitable light and the exposure made.

If printing from the film carried by the rollers 40 and 41 the adjustment may be made therewith by means of the knurled but- 50 tons 44 and 45 and the vignette may be ad- justed with reference to that film after which the exposure can also be made.

If it is desired to examine the picture or the setting thereof during the printing, 55 either of the doors may be opened by bending the springs 36 or 37 and moving it as above described.

I claim:

1. A printing frame having a compart- 60 ment at the back thereof, said compartment being divided into smaller compartments one on each end thereof with a central compart- ment extending between the end compart- ments, a closure for said central compart- 65 ment, an angular partition hinged at each

end of the frame and covering the back and inner end of each end compartment, said closure loosely abutting against the inner ends of said partitions.

2. A printing frame having a compart- 70 ment at the back thereof, said compartment being divided into smaller compartments one on each end thereof with a central compart- ment extending between the end compart- ments, a closure for said central compart- 75 ment, an angular partition hinged at each end of the frame and covering the back and inner end of each end compartment, said closure loosely abutting against the inner ends of said partitions, said closure com- 80 prising a central jamb with a door hinged on each side thereof.

3. A printing frame having a compart- 85 ment at the back thereof, said compartment being divided into smaller compartments one on each end thereof with a central compart- 90 ment extending between the end compart- ments, a closure for said central compart- ment, an angular partition hinged at each end of the frame and covering the back and inner end of each end compartment, said closure loosely abutting against the inner ends of said partitions, said closure com- 95 prising a central jamb with a door hinged on each side thereof, a button pivotally 95 mounted on said jamb and engaging the frame to hold said closure in position.

4. A printing frame having a compart- 100 ment at the back thereof, said compartment being divided into smaller compartments one on each end thereof with a central compart- 105 ment extending between the end compart- ments, a closure for said central compart- ment, an angular partition hinged at each end of the frame and covering the back and inner end of each end compartment, said closure loosely abutting against the inner ends of said partitions, said closure com- 110 prising a central jamb with a door hinged on each side thereof, a button pivotally 110 mounted on said jamb and engaging the frame to hold said closure in position, a spring connected to each of said hinged doors and engaging said jamb to hold the hinged doors in extended position.

5. A printing frame having a compart- 115 ment at the back thereof, said compartment being divided into smaller compartments one on each end thereof with a central compart- 120 ment extending between the end compart- ments, a closure for said central compart- ment, an angular partition hinged at each end of the frame and covering the back and inner end of each end compartment, said closure loosely abutting against the inner ends of said partitions, two spools mounted to rotate in each end compartment, each spool in each compartment constituting a pair with a corresponding spool in the other compartment, the spools of one pair being 125 130

capable of receiving a vignette mounted to travel between them and the spools of the other pair being capable of receiving a film mounted to travel between them.

5 6. A printing frame having a compartment at the back thereof, said compartment being divided into smaller compartments one on each end thereof with a central compartment extending between the end compartments, a closure for said central compartment, an angular partition hinged at each end of the frame and covering the back and inner end of each end compartment, said closure loosely abutting against the inner ends of 10 said partitions, two spools mounted to rotate in each end compartment, each spool in each compartment constituting a pair with a corresponding spool in the other compartment, the spools of one pair being capable of receiving a vignette mounted to travel between them and the spools of the other pair being capable of receiving a film mounted to travel between them, a spool mounted on each side of the frame, said spools being arranged in 15 20 pairs, said spools being capable of receiving a film or vignette mounted to travel between them, the film or vignette mounted on said last named spools being adapted to travel transversely to the film and vignette mounted to travel on said first named spools.

7. A closure for a printing frame having a central jamb with a door hinged on each side thereof, a block on said jamb, a button pivotally mounted on said block, a bow spring fastened at one end on each of said doors, the other end of each of said springs being adapted to yieldingly butt against 25 30 said block to hold said doors in line with said jamb.

40 8. A closure for a printing frame having a central jamb with a door hinged on each side thereof, a block on said jamb, a button

pivotsly mounted on said block, a bow spring fastened at one end on each of said doors, the other end of each of said springs 45 being adapted to yieldingly butt against said block to hold said doors in line with said jamb, said springs being adapted to swing away from said jamb to permit the opening of each door. 50

9. A printing frame having a compartment at the back thereof, said compartment being divided into smaller compartments one at each end thereof, an angular partition hinged at each end of the frame for closing 55 said compartments, a printing compartment located centrally of said frame between said angular partitions, a spring pressed closure for closing the back of said printing compartment, a hinged door for closing the 60 front of said printing compartment.

10. A printing frame having a compartment at the back thereof, said compartment being divided into smaller compartments one on each end thereof with a central compartment extending between the end compartments, a closure for said central compartment, an angular partition hinged at each end of the frame and covering the back and inner end of each end compartment, said 65 70 closure loosely abutting against the inner ends of said partitions, spools mounted to turn in each of said end compartments, said spools comprising a slotted stem having a shoulder and a reduced end on one side 75 thereof, a bearing plate adapted to receive said reduced end, a knurled handle fastened to the end of said reduced end, a coil spring interposed between said bearing plate and said shoulder on said stem to hold said 80 knurled handle in frictional contact with said bearing plate.

In testimony whereof I affix my signature.
CHARLES DE MARCO.
